UNITED STATES PATENT OFFICE.

ARTHUR O. HUBBARD, OF MINNEAPOLIS, MINNESOTA.

DESIGN FOR A CLOTHES WRINGER.

60,144.

Specification for Design.

Patented Jan. 3, 1922.

Application filed May 13, 1921. Serial No. 469,387. Term of patent 14 years.

To all whom it may concern:

Be it known that I, ARTHUR O. HUBBARD, a citizen of the United States, resident of Minneapolis, county of Hennepin, State of Minnesota, have invented a new, original, and ornamental Design for Clothes Wringers, of which the following is a specification, reference being had to the accompanying drawing, forming a part hereof.

The figure is a front elevation of a clothes wringer showing my new design.

I claim:

The ornamental design for a clothes wringer, as shown.

ARTHUR O. HUBBARD.
